FILAMENT SUPPORT

Dudley C. Pulliam, Chicago, Ill.

Application May 16, 1950, Serial No. 162,187

4 Claims. (Cl. 219—19)

1

This invention is concerned, in the broad sense, with a simple filament-support structure adapted for rapid and inexpensive assembly. More particularly, the invention is adapted to the manufacture of electrical heating elements and other electrical apparatus wherein it is desirable that an electrical conductor be supported in zigzag arrangement on a framework.

Practically all electrical appliances wherein electricity is used as a source of heat employ heating elements formed from strips of resistance wire, such as Nichrome. Since the total heat generated for a given line current is proportional to the length of the resistance element, it is usually essential that the resistance wire or ribbon be mounted in zigzag array on some sort of framework so as to permit a relatively great length of the ribbon to be carried within the limited dimensions of the toaster, iron, room heater, or other appliances.

The customary manner of making such devices in the prior art has been to wind the Nichrome ribbon by hand on a form made of mica, porcelain, or other suitable refractory material. Because of the large quantity of hand labor required, the cost of electrical heating elements has always been much higher than the cost of the raw materials themselves would justify.

I have provided a novel heating element wherein manual assembly is unnecessary. A heating element made according to my invention has only five parts, including the resistance ribbon itself, and it can be assembled in its entirety by simple machine methods. While my invention is particularly useful in the manufacture of heating elements for electrical appliances, it can readily be employed in any application wherein a filament, wire, or ribbon must be mounted inexpensively according to a zigzag pattern.

It may, therefore, be stated generally that the principal object of my invention is to provide a filament support, particularly adapted for use as a heating element, having a limited number of preformed parts readily susceptible of assembly by simple machine methods.

A further object of my invention is to provide a filament support, such as an electrical heating element, the assembly of which involves no hand guiding, threading, or winding of the filament.

Another object of my invention is to provide an electrical heating element, embracing a rigid framework, a mounted resistance ribbon, and clamps for making external connections to an electrical circuit, comprising a total of only five

2

parts, susceptible of assembly by automatic means.

Other objects and advantages of my invention will appear as the specification proceeds.

I have illustrated two typical embodiments of my invention in the accompanying drawing, of which Figure 1 is a top view of a heating element made according to my invention; Fig. 2, a side view, partly in section, of the embodiment of Fig. 1; Fig. 3, an end elevation view of the Fig. 1 embodiment of my invention; Fig. 4, a sectional view of the Fig. 1 embodiment of my invention, taken along the line 4—4 of Fig. 2; Fig. 5, an enlarged fragmentary sectional view of a portion of the structure shown in Fig. 2, the enlargement being designed to bring out certain details of the spring clamp structure which anchors the various parts of the invention together; Fig. 6 is a perspective view of a spring clamp employed in my invention; Fig. 7 is a top view of an alternative embodiment of my invention; Fig. 8 is a side view in section of the Fig. 7 embodiment of my invention; Fig. 9 is an end elevation view of the Fig. 7 structure; and Fig. 10 is a sectional view taken along the line 10—10 of Fig. 8.

In the drawing, referring now to Figs. 1-6 inclusive, I have shown my invention in the form of a heating element adapted for use with an electrical appliance such as a toaster. The frame structure is formed from two pieces of material—porcelain, or any other suitable high-temperature-resistant material, molded into suitable form. The lower of the two frame pieces, as seen in Fig. 2, is denoted 11; for convenience, I shall refer to member 11 as the "base member." The upper frame member is denoted 12; I shall refer to member 12 as the "cover member."

Base member 11 and cover member 12 are structurally similar except with respect to certain modifications along their side edges. Each of the two frame members 11 and 12 is generally comb-shaped, having a body portion and a plurality of long, thin fingers extending outward at right angles from the body portion. Exemplary fingers on base member 11 are denoted 13; exemplary fingers on cover member 12 are denoted 14.

The precise conformation of fingers 13 and 14 may be varied greatly as a matter of design; in general, however, it is desirable that the tip 50 of each finger be suitably modified to make it functional as a catch or guide member to receive the resistance ribbon which forms the heart of the heating element. In the particular embodiment shown, this catch or guide finger tip is formed by providing on each side of each finger

at its extremity a pair of narrow extensions, denoted 13a in the case of fingers 13 and 14a in the case of fingers 14. The body portion of each of the frame members 11 and 12 is provided with a plurality of reduced-width zones indicated on the drawing as zones 11a and 12a respectively. Extensions 13a are separated sufficiently to clear snugly the reduced-width zones 12a and, correspondingly, the extensions 14a are proportioned to clear snugly the reduced-width portions 11a on the base member 11. As a result, the members 11 and 12a can be joined in mating, interlaced relation, as shown in Fig. 2. As may be seen from Figs. 2 and 4, the abutment of end portions 12b and 11b of frame members 12 and 11 respectively occurs before the tips of fingers 13 and 14 come into contact with the body portions of frame members 12 and 11 respectively, so that a continuous zone of open space between the frame members 11 and 12 exists from one side thereof to the other, the two members abutting only at their end portions.

The end portions 12b of cover member 12 are provided with symmetrically disposed recesses 15 molded therein. As may be seen best from Fig. 5, recess 15 has inner walls which are generally parallel to the end surface of cover member 12 and the downwardly projecting fingers 16 which define the outer limits of recesses 15 are each provided with a smaller recess 16a roughly similar in shape to recess 15 but much smaller in size.

As may be noted from Fig. 3, the width of recesses 15 is somewhat less than the total thickness of cover member 12 so that the sides of recess 15 are wholly enclosed. Recesses 17, on the other hand, are closed off on only one side, leaving an open space 11c to permit the insertion of spring members 20 into recesses 17.

Base member 11 contains in each of its end portions symmetrically disposed recesses 17 designed for co-operation with recesses 15 and 16a in cover member 12. The recesses 17 are formed with an under-cut shoulder 18 which serves as a seat to hold securely in position spring clamp member 20 normally carried therein. In addition, the outer wall of each recess 17 is relieved at 19 to provide an external opening.

Spring clamps 20 are normally received within the recesses just described. A perspective view of a typical spring clamp 20 is shown in Fig. 6, from which it may be seen that each clamp has an elongated shank portion 21, a base portion 22 near its lower end and at right angles to shank 21, a curved spring portion 23, and a J-shaped portion 24 which is folded back on shank 21. The outer terminal edge of portion 24 may be sharpened to provide a cutting edge 25. Notches 26 are provided in the body of J-shaped portion 24 for a purpose to be hereinafter described. As may be noted from Fig. 5, base portion 22 normally seats against under-cut shoulder 18 in recess 17.

In my assembled heating unit, a resistance wire or ribbon 27 extends continuously from the edge 25 of the spring clamp 20 at one end of the frame structure through the zone of clearance between the fingers 13 and 14, zigzagging back and forth between the tips of the respective fingers, to the recess 15 at the other end of the frame structure, ribbon 27 finally terminating at the edge 25 of the clamp 20 mounted in the opposite end of the frame.

The wall of each of the recesses 15 is provided with a symmetrically arranged pair of projec-

tions 28 the function of which is to seat in notches 26 when spring clamp 20 is forced into recess 15, so as to lock spring clamp 20 therewith and prevent its being withdrawn once it has been seated.

As may be seen from Fig. 2 or Fig. 5, resistance ribbon 27 passes from the space between the frame members into recess 15, over the contour of spring clamp 20, between notches 28, and into recess 16a, terminating at knife edge 25.

It may be noted from Fig. 2 or 5 that spring portion 23 of spring clamp 20 provides, in co-operation with aperture 19, a receptacle for receiving a prong 32 to which wire 31 is soldered or otherwise affixed. Thus, by forcing prongs 32 into contact with springs 23, as shown in Fig. 5, electrical circuit connections to the respective terminals of resistance ribbon 27 may be made without the use of tools.

As may be seen from the drawing, my heating element has only five parts—frame members 11 and 12, a pair of spring clamps 20, and ribbon 27. In the assembly of a heating element made according to my invention, hand threading or winding of the ribbon 27 is not necessary. Ribbon 27 may be supplied to the assembly point by a reel having mild spring tension.

Normally my invention should be assembled on a flat surface, such as a horizontal table. The free end of ribbon 27 should be attached to a temporary anchor on the opposite side of the assembly table from the reel. A base member 11 is then supplied with spring clamps 20 suitably inserted into recesses 17, the shanks 21 projecting outward beyond recesses 17. Base member 11 is then slid into position for assembly with ribbon 27 passing between the various projections 13a and resting on the tips of the respective fingers 13. A cover member 12 is then placed on the assembly table on the opposite side of ribbon 27 from base member 11 and is then slid into mating, interlaced position with base member 11. The projections 14a guide ribbon 27 into position for seating on the tips of fingers 14, and, as the base and cover members are moved together, additional ribbon 27 is supplied from the reel. When the cover member 12 has reached the point of engagement with the outwardly projecting portions of spring clamps 20, ribbon 27 is guided around the portions 21 and 24 of spring clamps 20 and between projections 28. Member 12 is then forced into abutment with member 11, projections 28 lodged in notches 26, and the assembly of my invention is completed. The ends of ribbon 27 are then severed against knife edges 25, and the free end of ribbon 27 extending from the reel is moved over to the temporary anchor heretofore mentioned. The assembly table is then ready for another assembly operation.

The completed heating element thus assembled is mechanically strong, attractive in appearance, safe to use, and readily adapted for assembly into completed appliances such as toasters or room heaters.

In Figs. 7-10 inclusive, I have shown another embodiment of my invention, employing, however, the same basic principles. In this alternative embodiment, I use a pair of frame members denoted 111 and 112, 111 being the base member and 112 the cover member. Each of the two frame members is roughly rectangular in shape and is made in the form of a frame open in the center. The principal body portion of base member 111 is equipped at each end with a ledge or recess 113 having a small up-

wardly extending projection 114 to which a spring clamp 120 is secured by a bolt 121. Opposite and parallel to the body portion of base member 111 is a transverse top strip 111a having molded therein a plurality of notched projections 115. It will be understood that the frame members 111 and 112 are molded from a suitable refractory material, just as with the frame members in the Fig. 1 embodiment.

The cover member 112, constituting the other half of the frame structure, is also generally rectangular in shape and also has an open central portion. In the lower extremities of its sides there are provided a pair of recesses 116 which correspond to recesses 15 in the Fig. 1 embodiment and having the same general shape as that recess. Each of the sides of cover member 112 also contains a small recess 117 which corresponds to recess 16 in the Fig. 1 embodiment. The lower transverse side 112a of frame member 112 has molded in it a plurality of notched projections 119, spaced apart in the same manner as the notched projections 115 on transverse bar 111a and oriented with respect to projections 115 so that each of the projections 119 will pass midway between a pair of the projections 115 when the two frame members are slid together into mating or interlaced position.

The spring clamp members 120 are fingers similar to the clamp members 20 of the Fig. 1 embodiment, and the upper portions thereof are formed identically with those of clamps 20. To illustrate an alternative method of mounting the spring clamps, I have in this embodiment shown spring clamps bolted as aforesaid to the base member 111 and provided with spring extensions 121a to receive the electrical contact prongs 122.

In the assembled heating element of Figs. 7-10 a resistance ribbon 127 is mounted in zigzag array across the face of the frame, the ribbon being held in place by projections 115 and 119 and being anchored at its ends by spring clamps 120.

The assembly of the Fig. 7 embodiment of my invention is similar to that of the embodiment previously described. This form of my invention involves somewhat less structural frame material than the first embodiment and, on the other hand, does not provide the resistance ribbon with as much protection from mechanical damage as does the first form. Otherwise, the two embodiments employ the same principles of operation and have identical advantages of simplicity and rapid assembly.

While I have in this specification described in detail two embodiments of my invention for purposes of illustration, it will be understood that persons skilled in the art can make many changes and variations therein without departing from the spirit of my invention. It is accordingly my desire that the scope of my invention be not limited to the specific embodiments herein shown and described but determined primarily by reference to the appended claims.

I claim:

1. In combination, a pair of frame members carrying a plurality of oppositely disposed catch members and a filament wound zigzag between said catch members and supported alternately on a catch carried by one frame member and a catch carried by the other frame member, said frame

members being formed for interlaced mating to permit their being placed on opposite sides of the filament and slid into interlaced relation, and spring clamps on said frame members operative to secure the ends of the filament against movement and releasably to lock the frame members into interlaced position.

2. In combination, a pair of frame members carrying a plurality of oppositely disposed catch members and an electrically conducting filament wound zigzag between said catch members and supported alternately on a catch carried by one frame member and a catch carried by the other frame member, said frame members being formed for interlaced mating to permit their being placed on opposite sides of the filament and slid into interlaced relation, and spring clamps on said frame members operative to secure the ends of the filament against movement and releasably to lock the frame members into interlaced position.

3. In combination, a pair of co-operating frame members of substantially rectangular shape, each having a base strip, a leading strip and a pair of side strips joining the base and leading strips, said leading strips being each provided with a plurality of catch members staggered on the respective leading strips to permit interlaced passage of the catch members as the frame members are slid together, a filament having its ends secured to the frame members and being supported in zigzag array by the respective catch members, and a pair of spring clamps carried by said frame members, said clamps being operative to lock said frame members together in interlaced relation and providing also anchor means for the ends of said filament.

4. In combination, a pair of cooperating frame members, each of which is provided with a plurality of spaced catch members adapted to engage and hold a filament, said catch members on said respective frame members being staggered to permit interlaced passage as the frame members are slid together, a filament having its ends secured to the frame members and being supported in zigzag array by the respective catch members, and a pair of spring clamps carried by said frame members operative to lock the same together in interlaced relation and providing also anchor means for the ends of said filament.

DUDLEY C. PULLIAM.
